UNITED STATES PATENT OFFICE.

CHARLES H. KELLEY, OF BOSTON, ASSIGNOR TO CHARLES B. LANCASTER,
OF NEWTON, MASSACHUSETTS.

LASTING-MACHINE.

SPECIFICATION forming part of Letters Patent No. 361,363, dated April 19, 1887.

Application filed November 11, 1886. Serial No. 218,550. (No model.)

To all whom it may concern:

Be it known that I, CHARLES H. KELLEY, of Boston, in the county of Suffolk and State of Massachusetts, a citizen of the United States, 5 have invented certain new and useful Improvements in Lasting-Machines, of which the following is a specification.

My invention relates to improvements in the construction and mode of operation of machines for lasting boots and shoes, particularly 10 to those machines of the character shown in Letters Patent No. 307,763, granted November 11, 1884; and it has for its object to simplify and improve the construction of such machines.

In the accompanying drawings, Figure 1 is a longitudinal and vertical section of a machine in which my present improvements are embodied. Fig. 2 is a top plan view of the 20 same, omitting the gripping device and the apparatus by which the securing-strip is applied. Fig. 3 is a view of the machine in horizontal section on the line xx of Fig. 1, and Fig. 4 a view in vertical section on the line yy of Fig. 1. Fig. 5 is the same view, with the 25 addition of a device for applying the securing-strip. Figs. 6 to 9 are detail views, upon an enlarged scale, of specific portions of the machine, as will be hereinafter more fully described.

The frame A of the machine is trough-shaped, and within it is supported a system of four square shafts and beveled gears, B, operated by a driving-gear, C, (best shown in Fig. 35 4,) which is adapted, by means of a pinion and an ordinary clutch, to be driven, when desired, by any suitable source of power. Each of these shafts carries a cam, D, operating within a sliding box, E, to move the same toward and away from the center of the trough, 40 where the work to be lasted is placed. One of these boxes E is provided for each of the side-lasting devices, and one for the toe and heel lasting devices, respectively. The bearing of each box against its operating-cam is made adjustable (to regulate the time and extent of throw of the cam) by means of adjusting-screws $e'e$, as shown.

The side-lasting plates or slides F are pref-

erably formed each in two sections, and are removably secured to the tops of the sliding boxes. These slides are formed in the ordinary manner to correspond substantially in curve to the contour of the side of the sole of the shoe to be lasted.

The heel and toe lasting quadrants G G (best shown on an enlarged scale at Figs. 7 and 9) are mounted upon and carried by sliding boxes in the same manner, a plate, H, being interposed between the quadrants and the boxes, upon which plate the quadrants are pivoted, as shown at h , Figs. 1, 7, and 9. The rear portions, g, of the quadrants, extended beyond this pivot, form one portion of a lazy-tongs device, to the other portion of which, g' , is attached an operating-rod, I, which passes through a slot in an extension of the frame of the machine. Stop-nuts $i'i$ limit the motion of the rod I, which thus is made to operate the lazy-tongs to open and close the quadrants.

The last and upper are supported in the usual manner at the heel and toe, and suitable devices are provided for carrying the last and lasted shoe upward at the proper time in the operation of the machine, as will be hereinafter explained.

The gripping device for seizing and drawing up the edges of the upper is supported in any convenient manner—as, for example, by a swinging arm, J—so that it may be brought to 80 or away from its place of working. The device consists of a pair of plates, K L, in the lower of which, L, are mounted hollow depending shells, l, one for each gripper. The grippers themselves consist of a pair of jaws, M 85 M, pivoted upon a common pivot at the lower extremity of the shell L. To each of these jaws back of the pivot is pivoted a short link, m, which in turn is pivoted to the extremity of the rod N, by which the grippers are opened 90 and closed. This construction, which is again of the lazy-tongs order, is shown in detail at Fig. 8. The upper end of the rod N bears against the other of the two plates K, which can be moved toward or away from the plate 95 L by turning the screw-rod O, having a shoulder bearing against the plate K, through which it passes, and threaded at its lower extremity

in the plate L. A coiled spring, n, surrounding the upper part of each rod N, bears at one end against the enlarged end of the rod, (which for purposes of adjustment may be in the form 5 of a nut threaded upon the rod,) and the lower end of the spring rests upon a suitable bearing, n', surrounding the rod N where it passes through the plate K. From this construction it is obvious that raising the plate K away 10 from the plate L will cause the pinchers to open by the action of the springs, lifting the heads of the rods, while lowering the plate K toward the plate L by means of the screw will force the rods down, compressing their 15 rounding springs and closing the pinchers.

The entire gripping device is raised and lowered relatively to the last by means of the screw-rods P P, socketed at their lower ends in a downhold and threaded in the plate L. 20 These rods P P are connected by suitable gearing with a common operating-wheel, substantially as shown in the former patent.

The last is supported, as in the former patent, at the heel and toe by vertical posts Q Q, 25 and in order to obtain the upward motion of the last and the upper, after it has been lasted over the inner sole to hold it in place for the application of the securing-strip, these posts are made vertically movable, and are supported 30 at their lower ends by means of adjustable stop-nuts q upon a transverse bar, R. This bar in turn passes through and is held up by a stirrup-piece, S, which in turn is carried upon the short arm of a lever, T, fulerumed 35 upon a suitable projection from the bed of the machine. The long arm of this lever bears against a cam, U, operated by the main shaft of the machine, and so timed that after the lasting-plates have closed over the work the 40 cam U depresses the long arm of the lever T, thus raising the short arm, the stirrup S, the transverse bar R, and the posts Q Q, thereby carrying the lasted upper upon the last firmly against the under side of the lasting-plates.

45 The machine also contains a device for adjusting the position of the upper at the toe, so as to be engaged by the grippers, which is constructed substantially as described in the prior patent. This device (shown at V, Figs. 50 1 and 2) is supported upon wings v, extending horizontally from the posts p' on either side of the moving carriage which carries the toe-quadrants. It bears at the rear against springs which permit it to yield when the last 55 and upper are introduced into the machine, as in the former patent, and is provided with a retracting-lever operated by the advancing toe-carriage to move the device away before the toe-quadrants move over the upper at the 60 toe to last it.

To attach the retaining or securing strip by which the lasted upper is held in place over the inner sole, I employ a presser-block, W, whose acting face w (best seen in section in 65 Fig. 5) corresponds in general contour with the shape of the sole of the shoe to be lasted. This face w, I make of a strip of cork, as I

thereby obtain a more even and accurate pressure than has been given by rubber or any of the other substances heretofore employed. The 70 upper part of the presser-block W, I mount adjustably upon a swinging arm, W', pivoted at one end upon a suitable post, X, so that it may be raised and lowered radially, as shown in Fig. 5, and adapted at its other end to engage with a rod, W'', operated by a treadle, W'', by means of which the presser-block can be forced down upon the adhesive strip after it has been laid over the inner sole and the edges of the lasted upper, thus uniting the 80 two together. I further provide a slotted post or guide, X', into the slot of which the arm W' enters when brought down, as previously described, thereby centering the presser-block W over its work. 85

The series of operations performed by the machine is the same as was set forth in the prior patent, and a description of them therefore need not be repeated here. 90

I claim—

1. In a lasting-machine, the combination of the four-square system of shafts and beveled gearing B B B B herein described, the four cams D D D D, one mounted upon each of said shafts, and the four sliding boxes E E E E, 95 for carrying and operating the heel, toe, and side lasting plates, respectively, all substantially as herein set forth.

2. In a lasting-machine, the combination of the four-square system of shafts and beveled 100 gearing B B B B herein described, the four cams D D D D, one mounted upon each of said shafts, and the four sliding boxes E E E E, for carrying and operating the heel, toe, and side lasting plates, respectively, each of said 105 boxes being provided with adjustable bearings e e, for the purpose herein set forth.

3. In a lasting-machine, the combination, with the pivoted heel and toe lasting quadrants G G, of the lazy-tongs device g g g' g' 110 and its operating-rod I, provided with stop-nuts i i', for opening and closing said quadrants, all substantially as hereinbefore set forth.

4. In a lasting-machine, the improved gripping and releasing device herein described, consisting of the pivoted jaws M M, the links m m, and the operating-rod N, all substantially as set forth. 115

5. In a gripping device for lasting-machines, 120 the combination, with the plate L, of the hollow shell l, the pivoted jaws M M, links m m, and operating-rod N, all substantially as set forth.

6. In the gripping device of a lasting-machine, the combination of the plates K and L, the screw-rod O, passing through and bearing against the said plate K and threaded in the plate L, the hollow shell l, pivoted jaws M, links m m, operating-rod N, and springs n, 125 surrounding the upper part of said rod. 130

7. In a lasting-machine, the combination, with the vertical rods which support and raise the heel and toe of the last, of the transverse

bar R, stirrup-piece S, lever T, and a cam, U, operated from the principal source of power in the machine, to raise and lower the said posts, all substantially as set forth.

5 8. In a lasting-machine, the combination, with the presser-block W, of the supporting-post X, the slotted guiding-post X', rod W², and treadle W³, all substantially as herein set forth, and for the purposes herein specified.

In testimony whereof I have hereunto subscribed my name this 4th day of November, A. D. 1886.

CHARLES H. KELLEY.
